(57) **CLAIM**

The ornamental design for a light source for printer as shown and described.

DESCRIPTION

FIG. 1 is a front-top-right perspective view of a light source for printer according to our new design;

FIG. 2 is a rear-top-right perspective view thereof;

FIG. 3 is a bottom-right-rear perspective view thereof;

FIG. 4 is a bottom-left-rear perspective view thereof;

FIG. 5 is a front view thereof;

FIG. 6 is a rear view thereof;

FIG. 7 is a top view thereof;

FIG. 8 is a bottom view thereof;

FIG. 9 is a right side view thereof;

FIG. 10 is a left side view thereof;

FIG. 11 is an enlarged view of a portion of the light source for printer shown in rectangle 11 in FIG. 3; and,

FIG. 12 is an enlarged view of a portion of the light source for printer shown in rectangle 12 in FIG. 4.

The dashed lines show portions of the light source for printer that form no part of the claimed design. The dashed-dotted lines depict the boundaries of the enlarged views that form no part of the claimed design.
